Fig. 3.

Fig. 4.

Fig. 5.

Fig. 6.

FIGURE 1 is a perspective view of a lavatory showing my new design;

FIGURE 2 is a plan view thereof;

FIGURE 3 is a view thereof looking along the line 3-3 in FIG. 2;

FIGURE 4 is a view thereof looking along the line 4-4 in FIG. 2;

FIGURE 5 is a fragmentary view thereof looking along the line 5-5 in FIG. 2;

FIGURE 6 is a view thereof looking along the line 6-6 in FIG. 2.

The dominant features of the design reside in the portions shown in full lines.

The present application constitutes a continuation of my copending application Serial No. D.81,457, filed August 26, 1964 now abandoned.

I claim:

The ornamental design for a lavatory, substantially as shown and described.
